(57) **CLAIM**

The ornamental design for a remote control housing, as shown and described.

DESCRIPTION

FIG. 1 is a top perspective view of a remote control housing showing my new design;

FIG. 2 is a bottom perspective view thereof;

FIG. 3 is a top plan view thereof;

FIG. 4 is a bottom view thereof;

FIG. 5 is a right side elevational view thereof;

FIG. 6 is a left side elevational view thereof;

FIG. 7 is front elevational view thereof; and,

FIG. 8 is a rear elevational view thereof.

The broken lines illustrate portions of the remote control housing that form no part of the claimed design.
